(57) CLAIM

The ornamental design for a bag holder, as shown and described.

DESCRIPTION

FIG. 1 is a first perspective view of a bag holder showing the new design;

FIG. 2 is a second perspective view of the bag holder;

FIG. 3 is a side view of bag holder;

FIG. 4 is the other side view of the bag holder;

FIG. 5 is a top view of the bag holder;

FIG. 6 is a bottom view of the bag holder;

FIG. 7 is a rear view of the bag holder, and,

FIG. 8 is the front view of the bag holder.

The broken lines in the Figures showing a handle are for environmental purposes only and form no part of the claimed design.
